UNITED STATES PATENT OFFICE.

JOHN A. HILLERICH, OF LOUISVILLE, KENTUCKY, ASSIGNOR TO HILLERICH & BRADSBY CO., OF LOUISVILLE, KENTUCKY, A CORPORATION OF KENTUCKY.

GOLF-CLUB HEAD.

Application filed October 19, 1925. Serial No. 63,507.

The invention relates to golf clubs, and more particularly to the head of such clubs, as drivers and the like, and has for its object primarily to improve the driving and carrying power of the club.

Heretofore various materials including ivory, have been inserted in the striking faces of golf clubs, and my improvement is directed to this subject, with a view to lessening the cost of manufacture and improving the elasticity and propelling power of the driving face of the club.

The invention consists in the parts and combinations thereof hereinafter set forth and claimed.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:—

Fig. 1 is a front view of the head of a golf driver, showing the striking face thereof containing my invention.

Fig. 2 is a horizontal sectional view of the same on line II—II of Fig. 1.

Figs. 3 and 4 are side and plan views of one of the inserts.

Referring to the drawings, A indicates the head of the club, ordinarily of a suitable strong wood. This head is formed in its front driving face with a recess *r* of suitable depth, say one-fourth of an inch and extending from the bottom to the top of the club. This recess is preferably longer at the bottom so that it tapers upwardly.

B is a retaining plate, which may be of fiber, hard rubber, or the like, which is adapted to fit neatly within said recess, in which it is secured by screws C as illustrated, these screws extending well into the body of the head.

D indicates one of the inserts made of relatively hard and elastic material, such as ivory or the like. The insert is of outwardly tapering form, so that its inner face *d* which rests against the face *a* of the recess is wider and larger than the external striking face *d'*.

The retaining plate B is formed with an aperture *b* of corresponding shape, so that when the insert is placed in said aperture and the retaining plate is secured in said recess *r* against the face *a* of the head the insert is very firmly held and cannot by any possibility escape.

It will be understood that I may employ as many of said inserts as necessary or desirable, and arrange them in any suitable manner, for instance as illustrated in the drawing, in which five of said inserts are shown.

The conical form of the insert strengthens it very much for driving purposes, so that it is not likely to split or to chip off at its outer corner.

What I claim is:

1. A golf club head having a portion of its striking face formed by the outer and smaller ends of hard and elastic frusto-conical bodies, in combination with said bodies, and means separate from said bodies for engaging the sloping sides of said bodies and holding their wider ends in place against the body of the head.

2. A golf club head having its front striking face recessed, hard and elastic frusto-conical bodies arranged with their larger bases against the wall of said recess, a retaining plate separate from said bodies having apertures of frusto-conical shape and arranged so as to receive and retain said bodies in place, and means for securing said plate against the face of the head of the club.

In testimony whereof I affix my signature.
JOHN A. HILLERICH.
